No. 802,338.

PATENTED OCT. 17, 1905.

A. J. THORNLEY.
GYMNASIUM APPARATUS.
APPLICATION FILED MAY 2, 1905.

FIG. 1.

UNITED STATES PATENT OFFICE.

ALBERT J. THORNLEY, OF PAWTUCKET, RHODE ISLAND, ASSIGNOR
TO NARRAGANSETT MACHINE COMPANY, OF PAWTUCKET, RHODE
ISLAND.

GYMNASIUM APPARATUS.

No. 802,338.

Specification of Letters Patent.

Patented Oct. 17, 1905.

Application filed May 2, 1905. Serial No. 258,451.

To all whom it may concern:

Be it known that I, ALBERT J. THORNLEY, a citizen of the United States, residing at Pawtucket, in the county of Providence and State 5 of Rhode Island, have invented a new and useful Improvement in Gymnasium Apparatus, of which the following is a specification.

This invention has reference to an improvement in the means for securing parallel bars 10 or other gymnasium apparatus to the floors of gymnasiums.

In the use of parallel bars, horses, or other exercising apparatus in the gymnasium it is required that the apparatus should be firmly 15 secured to the floor of the gymnasium when in use. When not in use, they are removed from the floor of the gymnasium, so as to give an unobstructed floor-space for class exercises or other purposes.

20 The object of my invention is to detachably secure the supports of parallel bars or other gymnasium apparatus to the floor of the gymnasium.

25 A further object of my invention is to provide the floors of gymnasiums with sockets permanently embedded in the floor, said sockets being adapted to receive the lower ends of the supports of parallel bars or other gymnasium apparatus to firmly hold and lock 30 the same in the sockets when in use with means for closing the openings in the sockets flush with the floor-line when the apparatus is removed from the sockets.

35 My invention consists in the peculiar and novel construction of sockets for gymnasium apparatus, said sockets being embedded in the floor of the gymnasium flush with the floor-line and adapted to firmly hold the supports of parallel bars or other gymnasium apparatus 40 to lock the same in the sockets when in use, with means for closing the opening in the sockets when not in use, consisting of a hinged cover, and other details of construction, as will be more fully set forth hereinafter.

45 The floors of gymnasiums are usually constructed of concrete or cement covered with a hard-wood flooring, such as maple. In carrying my invention into practice I construct the sockets in pairs connected together by a 50 plate and strengthening-web, the sockets extending above the plate the thickness of the board flooring, so as to bring the top of the sockets flush with the floor-line.

Figure 1 is a top plan view of my improved double socket, showing the right-hand socket 55 closed and the support of a gymnasium apparatus locked in the left-hand socket. Fig. 2 is a vertical sectional view taken lengthwise through the double socket, showing the right-hand socket closed by a hinged cover and the 60 lower end of the support of a gymnasium apparatus in the left-hand socket. Fig. 3 is a detail plan view looking at the under side of the left-hand socket, and Fig. 4 is an enlarged detail view of the hinged cover removed from 65 the socket and looking at the under side of the cover.

In the drawings, *a* indicates my improved double socket; *b*, the lower end of a support 70 for parallel bars, horses, or other gymnasium exercising apparatus, and *cc* the floor-line of a gymnasium, as indicated in broken lines in Fig. 2. The double socket *a* consists of a pair of inverted truncated cone shaped sockets *a'* *a'*, connected together by the plate *a*² and the 75 strengthening-web *a*³, all formed integral, as shown in Fig. 2. This double socket *a* is cast in metal, preferably in iron, and is adapted to be embedded in a concrete or cement floor. When timbers are used in the floor of the 80 gymnasium, the double socket is secured to the timbers by bolts through the holes *a*⁴ *a*⁴ in the plate *a*². Each socket *a'* is constructed to have the finished internal annular ribs *a*⁵ *a*⁵. These ribs are located adjacent the upper and 85 lower ends of the sockets. The upper end *a*⁶ of the socket where it extends above the plate *a*² is approximately square and has the recessed portion *a*⁷, shaped to receive the circular cover *a*⁸, as shown in Figs. 1 and 2. This 90 cover *a*⁸ has the hinge portion *a*⁹ pivotally secured in the recess *a*⁷ by the pin *a*¹⁰, which extends through the upper end *a*⁶ of the socket and through the hinge portion *a*⁹ of the cover, as shown in broken lines in Fig. 1. A lug *a*¹¹ 95 is formed on the under side of the cover adjacent the hinge portion *a*⁹, and an adjusting-screw *a*¹² is screw-threaded through the lug, as shown in Figs. 2 and 4. The cover when in the closed position closes the upper open 100 end of the socket flush with the floor-line.

The cylindrical metal support *b* has the inverted truncated cone shaped lower end *b*', on which is formed the annular flanges *b*² *b*², located at the base and end of the cone. These 105 flanges are shaped and finished to fit the internal

annular ribs a^5 a^6 of the sockets a' a' , as shown in Fig. 2. The upper flange b^2 is larger than the stem of the support b and forms the circular ledge b^3 . A recess b^4 is formed in the 5 side of the support and extends upward from the ledge b^3 . A latch b^5 , having the finger-piece b^6 , the outwardly and downwardly extending lower end b^7 , and the vertical slot b^8 , is movably secured to the support b above the 10 recess b^4 by the screws b^9 b^9 through the slot b^8 in the latch.

In the construction of parallel bars or similar exercising apparatus four of the supports b are used, the lower end of each support having the cone-shaped end b' , the recess b^4 , and the latch b^5 , as shown in Fig. 2. For this purpose two of the double sockets a are embedded in the floor of the gymnasium the required distance apart. When not in use, the covers 15 a^8 a^8 of the sockets are closed, thus presenting a flat unbroken surface flush with the floor-line. When the exercising apparatus is to be used, the covers a^8 a^8 of the sockets are opened, the cone-shaped ends b' b' of the supports b of 20 the apparatus are placed in the cone-shaped sockets a' a' , and each support locked in position by raising the latches b^5 , bringing the cover a^8 against the side of the supports b , with the screw a^{12} bearing on the ledge b^3 of 25 the support and lowering the latch to bring the lower end b^7 over the edge of the cover, thus locking the cover to the support and the support to the socket. By this construction the supports are firmly held in the sockets by 30 the wedging action of the cone-shaped ends in the cone-shaped sockets, the supports are locked to the sockets, thereby preventing accidents by the supports jumping out of the sockets when the apparatus is in use, and the 35 supports are easily removed from the sockets by raising the latches on the supports.

It is evident that my improved socket could be constructed and used as a single socket, if required, or a plurality of sockets could be 40 connected together by a plate and web, as shown in Fig. 2, without materially affecting the spirit of my invention.

Having thus described my invention, I claim as new and desire to secure by Letters Patent—

50 1. In a gymnasium apparatus, a truncated-cone-shaped socket, a hinged cover for closing the upper open end of the socket, and means carried by the cover for locking a support to the socket.

55 2. In a gymnasium apparatus, a double socket consisting of two truncated-cone-shaped sockets having internal annular ribs, means for connecting the sockets consisting of a plate and strengthening-web, and means for 60 closing the open upper end of the sockets, as described.

3. In a gymnasium apparatus, a double socket consisting of two inverted truncated cone shaped sockets having internal annular 65 ribs, a plate and strengthening-web connecting

the sockets all formed integral, and hinged covers for closing the upper open end of the sockets, as described.

4. In a gymnasium apparatus, the combination of a double socket consisting of two inverted truncated cone shaped sockets having internal annular ribs, and a plate and strengthening-web connecting the sockets all formed integral, of supports for the apparatus each support having a truncated-cone-shaped lower end on which are annular flanges adapted to fit the annular ribs in the sockets, as described. 70 75

5. In a gymnasium apparatus, the combination of an inverted truncated cone shaped socket having internal annular ribs, a hinged cover, and means for securing the socket in the floor flush with the floor-line, and a support having a truncated-cone-shaped lower end on which are annular flanges adapted to fit the annular ribs in the socket, and means for locking the support to the socket, as described. 80 85

6. In a gymnasium apparatus, the combination with a double socket, a plate and strengthening-web connecting the sockets, and hinged covers for closing the upper open 90 end of the socket, of supports for the apparatus, the lower end of each support formed to fit the socket, and means for securing the support to the sockets, for the purpose described. 95

7. In a gymnasium apparatus, the combination with a double socket, a plate and strengthening-web connecting the sockets, and hinged covers for closing the upper open 100 end of the sockets, of supports for the apparatus the lower ends of which are formed to fit the sockets, and means carried by the hinged covers for locking the supports to the 105 sockets, as described.

8. In a gymnasium apparatus, the combination with two sockets, a plate and strengthening-web connecting the sockets all formed integral, a cover pivotally secured to the top of each of the sockets, a lug forming part of the cover, and a set-screw in screw-thread engagement with the lug, of supports for the apparatus the lower ends of which are formed to fit the sockets and provided with means with which the set-screw 110 carried by the lugs on the covers may come in contact to lock the supports to the sockets, 115 as described.

9. In a gymnasium apparatus, the combination with two sockets, a plate and strengthening-web uniting the sockets, a cover pivotally secured to the top of the sockets, a lug on each of the covers, a set-screw in screw-thread engagement with the lug, of supports for the apparatus the lower 120 ends of which are formed to fit the sockets, means on the support with which the set-screws carried by the lugs on the covers come in contact to lock the support to the 125 socket, and means carried by the supports 130

to lock the covers to the supports, as described.

10. In a gymnasium apparatus, the combination of a double socket *a* consisting of a pair of inverted truncated cone-shaped sockets *a'* *a'* connected together by a plate *a²* and a web *a³* all formed integral, each socket having the internal annular ribs *a⁵* *a⁶*, the recessed portion *a⁷*, and the cover *a⁸* which has the hinge portion *a⁹* pivotally secured to the socket by the pin *a¹⁰*, and a lug *a¹¹* supporting the adjusting-screw *a¹²*, and supports for the apparatus, each support *b* having an inverted truncated cone-shaped lower end *b'* on which is formed the annular flanges *b²* *b²* adapted to fit the inner annular ribs *a⁵* *a⁶* of the sockets, the circular ledge *b³*, the recess

b⁴ in the side of the support extending upward from the ledge *b³*, and a latch *b⁵* having the finger-piece *b⁶*, the outwardly and downwardly extending lower end *b⁷*, and the vertical slot *b⁸* movably secured to the support *b* above the recess *b⁴* by screws through the slot *b⁸* in the latch, whereby the lower ends of the supports are firmly secured in the sockets and locked to the sockets, as described. 20 25

In testimony whereof I have signed my name to this specification in the presence of two subscribing witnesses.

ALBERT J. THORNLEY.
